FIG. 4

FIG. 1 is a view taken on a plane parallel to the top surface of the merchandising display tray for bottles or like objects showing my new design;

FIG. 2 is a side elevation thereof;

FIG. 3 is a front elevation thereof;

FIG. 4 is a rear elevation thereof.

I claim:

The ornamental design for a merchandising display tray for bottles or like objects, as shown and described.
